UNITED STATES PATENT OFFICE.

CHARLES A. SALISBURY, OF NEW YORK, N. Y.

PROCESS OF CONSTRUCTING FABRIC STRUCTURES.

1,358,582.

Specification of Letters Patent.

Patented Nov. 9, 1920.

Application filed November 24, 1919. Serial No. 340,425.

To all whom it may concern:

Be it known that I, CHARLES A. SALISBURY, a citizen of the United States, and a resident of the city of New York, borough of Manhattan, in the county and State of New York, have invented a new and Improved Process of Constructing Fabric Structures, of which the following is a full, clear, and exact description.

10 This invention relates to new and useful improvements in theatrical equipments, and it pertains more particularly to a mat or cloth covering for stage surfaces, commonly known in the art as ground cloth, stage cloth, floor cloth, etc.

The present invention is a continuation in part of my application filed April 18, 1919, and patented Mar. 30, 1920, No. 1,335,607, to which cross reference is here 20 made.

The surfaces of stage floors are generally covered with a removable canvas or other floor covering, and it is this class of invention to which the present invention pertains.

25 Devices of this character are subjected to rough usage as the result of continuous walking, dancing, and the like, and it is the primary object of the present invention to construct a device of this character which

30 will be capable of withstanding the excessive wear and strain to which it is subjected.

Owing to the large surface to be covered, devices of this character are made from a plurality of individual strips of canvas, khaki, or other suitable material, which strips are sewed together to form a single mat, and a further object of the present invention is to so arrange the several strips of material in such a manner that the seams 35 by which they are secured together are protected from the rough usage heretofore mentioned.

40 It is another object of the invention to provide means by which the device may be retained in proper position on the stage surface.

45 It is a still further object of the invention to so construct the retaining means and reinforce its attachment to the marginal edges of the floor cloth, as to render it capable of withstanding the strains of properly stretching without injuring the same.

50 With the above and other objects in view, reference is had to the accompanying drawings, in which—

55 Figure 1 is a perspective view of the com-

pleted floor cloth constructed in accordance with the present invention;

Fig. 2 is a detail sectional view showing the initial step in the operation of securing the several strips together;

Fig. 3 is a detail sectional view on the line 3—3 of Fig. 1;

Fig. 4 is a detail perspective view of the rear face of the "cloth."

Referring more particularly to the drawings, the reference character A designates the floor cloth, and said floor cloth is formed from a plurality of individual strips of canvas, khaki, or other suitable material designated by the reference character 5. In securing these strips together, they are positioned as shown in Fig. 2, *i. e.*, one strip on the other, the upper strip having its edge 70 positioned slightly back from the edge of the under strip as indicated by the reference character B in Fig. 2. When two of the strips have been thus positioned, they are secured together by a double line of stitching 6. These lines of stitching 6 may be arranged parallel to each other, as shown in the drawings, or, if desired, said lines of stitching may be made one upon the other.

After two strips 5 have been secured together in this manner, the upper strip is folded to the position which it occupies in Fig. 3, as designated by the dotted line position and arrow D in Fig. 2. This operation provides a loop or fold 7, which overlies the 75 double stitching 6, and serves as a protection therefor in such a manner that as the floor cloth is walked upon, the stitching 6 is not exposed to the wear incident thereto. After the upper strip has been folded over, 80 it is secured in its folded position by means of a single line of stitching 8.

85 After a sufficient number of the strips have been secured together in this manner to form a floor cloth of the desired shape and size, the marginal edge of the completed cloth is provided on its under side with a strip of suitable reinforcing material 9. The strip of reinforcing material 9 is then provided with a plurality of spaced openings, as is also the marginal edge of the floor cloth, and in each of these openings is preferably placed a metal gromet 10, which forms the means together with a suitable rope or lacing, for securing and properly stretching the floor cloth in operative position. In lieu of the metal gromets 10, hand-worked gromets may be employed, and

in addition to the reinforcing strip 9 preventing tearing of the floor cloth during the stretching operation, it also provides means by which the floor cloth may be properly secured in place as by means of tacks or similar driven fastenings.

From the foregoing description, it will be apparent that the present invention provides a floor cloth in which while one of the seams, *i. e.*, the stitching 8, is exposed to wear, the several sections which form the floor cloth are secured together by means of a plurality of lines of stitching, which are completely protected from the wear incident to the use for which the floor cloth is intended. Should the line of stitching 8 become worn to such an extent as to permit of the separation of the strips 5 at the point of such line of stitching, the double stitching 6 will serve to retain the several strips in proper position until such a time as the material from which the "cloth" is made wears through sufficiently to expose the double line of stitching 6 to service.

25 Claims:

1. The process of constructing fabric structures, which consists in placing strips

of material in superimposed relation with the edge of one strip spaced from the edge of the adjacent strip, securing said strips together by a plurality of stitches, subsequently folding one of said strips of material with respect to the other in such a manner as to conceal said plurality of stitches, and subsequently securing said strips in such relation with a plurality of exposed stitches, said stitches passing through the loop of the folded strip and beyond the inclosed edge of the spaced strip.

2. The process of constructing fabric structures which consists in placing strips of material in superposed relation with the edge of one strip spaced with respect to the edge of the adjacent strip, securing said strips together by a plurality of stitches, subsequently folding one of said strips with respect to the other strip to conceal said stitches, and retaining said strip in folded position by means of a line of exposed stitching passing through both of said strips at a point between the edge of the spaced strip and the edge of the strip to which it is attached.

CHAS. A. SALISBURY.
